HENRY W. FISHER, OF PITTSBURGH, PENNSYLVANIA, ASSIGNOR TO STANDARD UNDER-GROUND CABLE COMPANY, OF PITTSBURGH, PENNSYLVANIA, A CORPORATION OF PENNSYLVANIA.

METHOD OF FORMING ELECTRIC CABLES AND APPARATUS THEREFOR.

1,009,731.

Specification of Letters Patent. Patented Nov. 28, 1911.

Application filed October 21, 1910. Serial No. 588,285.

To all whom it may concern:

Be it known that I, HENRY W. FISHER, residing at Pittsburgh, in the county of Allegheny and State of Pennsylvania, a citizen of the United States, have invented or discovered certain new and useful Improvements in Methods of Forming Electric Cables and Apparatus Therefor, of which improvements the following is a specification.

My invention relates to electric cables.

More particularly my invention has to do with the final step in the manufacture of cables, sheathed in lead or other materials, and the object of my invention is to provide a method of manufacturing such electric cables to the end that a more efficient cable may be secured. The means employed in accomplishing this method are illustrated in the accompanying drawings which form a part of my specification.

In these drawings Figure 1 is a plan of a kettle with its lid removed and a portion of a lead press with a means for carrying the core, submerged in the insulating compound, from the former to the latter, and Fig. 2 is a section taken on line II—II of Fig. 1 showing, in addition, the lid in place.

Like parts bear the same reference numerals in both figures.

By the term "core", herein used, is meant the conductors after they have been surrounded with coverings of coherent insulating materials, such as paper fabrics or other suitable materials, and before the same has been covered with a sheath.

It is well known that the quality of an electric cable, aside from its conductivity and structural strength, is largely dependent upon the efficiency of its insulation. This insulation is accomplished primarily by fabrics and papers arranged in suitable ways about the conductors to accomplish their separation from each other and from any possible adjacent conductors. It has been discovered that these insulating methods in themselves embody two weak points, namely, accumulated moisture and air spaces. These points of weakness have been temporarily eliminated by placing the core in a reservoir capable of being made air tight, and treating the said core therein as hereinafter described. The reservoir is first heated, so as

to drive the moisture from the core, and a vacuum is created therein. In the pressure of this vacuum the air, incased in the various parts of the core, will be extracted, and any moisture that may have remained after the heating of the core will be vaporized. At this point advantage is taken of the vacuum to inject a heated insulating compound, of more or less fluid consistency, into the existing cavities. The said compound is introduced through any suitable opening, after which the bath, with its submerged core, is subjected to atmospheric pressure. It will be apparent that in this heated state the insulating compound under the pressure of the air will impregnate the entire core, thereby filling the cavities, hence eliminating the weak points caused by the same.

The core is kept submerged in the insulating compound until both are cooled to a normal temperature, to the end that, as the compound in the interior of the core shrinks, while cooling, additional compound will flow therein. After the core has been treated as thus far described, the present practice is to take it from the compound within the reservoir and place it in a suitable position to be fed into the lead-press. In doing this it will be apparent, first, that the semi-viscous insulating compound will drip from the exterior of the core, thereby rendering it liable to the formation of new air cavities; and second, that these air cavities will be incased within the lead sheath together with a portion of the air surrounding the core. Therefore the cable will be weakened just in proportion to the amount of air incased within the lead sheath during the sheathing process. It is toward the improvement of this last step in the method of forming cables that I direct my invention, and the improvement consists in providing a means whereby the core, after it has once been submerged in insulating compound, may be kept surrounded by the same until the core is inclosed within its lead sheath.

Any suitable means may be employed to bring the core in its submerged condition to a suitable position for leading. As for example, the kettle may be transferable from one position to another by means of trucks

and a system of tracks, or the kettle may be stationary and the core conducted therefrom through a trough of suitable length and proportion to allow the core to cool 5 while on its passage to the lead-press. Preferably I employ the former method, namely, a system of transferable kettles whereby each kettle, containing a reel of core, may, in the course of procedure, be taken successively 10 to steam heating pipes, vacuum pump, insulating compound tank and cooler; and in these successive positions the moisture is driven from the core, air is exhausted from the kettle, the core within the 15 kettle is submerged in hot insulating compound and the bath is cooled to a more viscid condition.

The kettle may be of any suitable form and material to accomplish the desired end. 20 As shown it consists of the main body 1 and a lid 2, between which is interposed a suitable gasket 22 to insure an air-tight connection. The outside of the kettle may be provided with suitable trunnions 3 for handling 25 the same, and on the inside are trunnion bearings 4, on which the contained reel 5 is rotatably supported. The kettle is further provided with suitable openings to accomplish the various steps in the treatment 30 of the core as heretofore described. Near the top of the kettle I conveniently provide a pipe and valve 6, whereby connection may be made to the air pump when it is desired to produce a vacuum within the said kettle, 35 and at the top is an opening 21, through which air may enter after the insulating compound has been admitted. At the bottom is a pipe 7, through which the insulating compound may be conveniently entered, 40 and the pipes 8 and 9, connecting with the steam heating coil 10, provide means of attaching the same to a steam supply pipe. It will be understood of these various connection pipes that they are preferably secured 45 rigidly to the kettle and are so constructed that their connections to the steam-pipe, air-pump, and vacuum-tank may be broken, thus leaving the kettle with its small protruding pipes free to be taken 50 from place to place.

Attached to the kettle I provide means for unreeeling the core, to the end that it may be constantly submerged in the insulating-compound. As shown in the drawings 55 I accomplish this by using a conduit 11 of such shape that the core in passing out will not be sufficiently bent to cause any injury thereto, an air-tight gate valve 12 to retain the insulating-compound when the core is 60 not being leaded, and an open top box 13. The top of this box 13 is placed at a level supposedly above that of the compound in the kettle. However, to guard against the compound overflowing the box 13 coincident 65 with the opening of the valve 12 in case

too much compound had been allowed to enter the kettle, I provide an escape pipe 14. Furthermore the end of the box 13 has a cylindrical protrusion, suitably threaded that connection may be made to a flexible 70 pipe 15, which connects the kettle with the lead-press.

The lead-press may be of any suitable form and type of construction. The essential parts thereof may be arranged as shown 75 in Fig. 2, wherein the block 16 contains the hot lead chamber 17, in which the proper pressure is sustained by the plunger 18. The block 16 is suitably threaded for connection to the nut 19, one end of which is 80 connected to the flexible hose 15. The other end of the said nut bears against the thimble 20, to the end that a turning of the nut will change the thickness of the forming lead sheath. The nut and thimble may be of 85 any form such that they permit the passage of the core surrounded by the insulating compound.

The operation of my invention is as follows:—A reel of core 5 is rotatably mounted 90 upon the trunnion bearings 4 in the interior of the kettle. Upon the free end of the core a clevis is attached and the core unreeled sufficiently to permit its clevised end to lie close to the gate-valve. The core is then 95 treated in the ordinary manner by heating it, subjecting it to a vacuum, impregnating it with insulating compound, and then allowing the kettle with its contents to cool to a working temperature. When a working 100 temperature of the compound has been reached, the kettle is connected to the lead-press and the gate valve opened, after which the compound will flow into the box 13, the pipe 15, the nut 19, the thimble 20 and into 105 a short piece of lead pipe that has been previously run, the end of which has been closed. By means of a suitable hook, manipulated from the box 13, the clevised end of the core is engaged and pulled into the 110 said box where the clevis is removed. This box is further used to give access to the core so that it may be pushed along until its end reaches the posterior end of the thimble, 115 after which the pressure of the lead sufficiently pulls upon the core to cause it to unreeel.

It will be observed of my invention that, after the core has been placed in the insulating compound bath, it is at no time exposed to the air. Furthermore, in case of extraordinary speed being required in the manufacture of a cable, the core may be leaded while the compound is in a hot fluid state, thereby eliminating the time required 120 for cooling and at the same time preventing the compound from flowing out of the core. However, I prefer, for reasons hereinbefore explained, to sheath the core after the compound has cooled. 125

I claim herein as my invention:

1. The herein described method of manufacturing sheathed insulated cables which consists in driving the moisture and air from a core by subjecting it to a vacuum, flooding the moisture and air-riden core with insulating compound, drawing the core from said compound and simultaneously with its withdrawal surrounding said core to the exclusion of air with a sheath. 35
2. The herein described method of manufacturing insulated lead-sheathed cables, which consists in maintaining a bath of insulating compound in fluid state at an elevated temperature, with an extended portion in viscid and contracted state at reduced temperature, immersing a core in the fluid portion of said bath, and withdrawing such core from said bath through the viscid portion thereof, and, simultaneously with the withdrawal of said core from such bath surrounding it and its adhering envelop of insulating compound, to the exclusion of air, with a sheath. 40
3. In an apparatus for making sheathed and insulated electric cables, a combination of a sheath-applying mechanism, a kettle which when closed may be made air-tight and within which a reel of core may be immersed in insulating compound and a conduit leading from said kettle to said mechanism, through which a core, enveloped in compound, may be fed immediately to the 45
- sheath-forming means, substantially as described. 45
4. In an apparatus for making lead-sheathed electrical cables, the combination of a lead press, a conduit leading to said lead press, and a kettle, within which a core may be immersed in an insulating compound 50 and provided with an outlet passageway, through which a core may be withdrawn while still immersed in the compound, a valve in said passageway capable of hermetic closure, and an opening in said passageway adjacent to but beyond said valve, affording access to the interior of said passageway, substantially as described. 55
5. In an apparatus for making sheathed and insulated electric cables, the combination of an air-tight kettle provided with connections for the removal of air and moisture and the introduction of insulating compound, a sheath-applying mechanism, and a conductor leading from said kettle to said sheath-applying mechanism, through which a cable core constantly submerged in insulating compound may advance, substantially as described. 60

In testimony whereof, I have hereunto set my hand.

HENRY W. FISHER.
